UNITED STATES PATENT OFFICE.

FREDERICK PRÉTAT, OF WATERBURY, CONNECTICUT, ASSIGNOR TO THE INTERNATIONAL SILVER COMPANY, OF MERIDEN, CONNECTICUT.

DESIGN FOR A HANDLE FOR A SPOON OR SIMILAR ARTICLE.

SPECIFICATION forming part of Design No. 33,154, dated September 4, 1900.

Application filed July 26, 1900. Serial No. 24,945. Term of patent 14 years.

To all whom it may concern:

Be it known that I, FREDERICK PRÉTAT, a citizen of the United States, residing at Waterbury, in the county of New Haven and State 5 of Connecticut, have invented and produced a new and original Design for a Handle for a Spoon or Similar Article; and I do hereby declare the following to be a full, clear, and exact description of the invention, such as will enable others skilled in the art to which it appertains to make and use the same.

Referring to the accompanying drawings, Figure 1 is an elevation showing the obverse side of my new design; Fig. 2, an elevation 15 showing the reverse side of said design, and Fig. 3 a cross-section taken at the line $x-x$ of Fig. 1.

Similar letters of reference denote like parts in the several figures of the drawings.

As shown in the drawings, the leading or material features of my design, as to the obverse side, are the oval medallion *a* at the top of the handle, the beaded ornamentation *b* surrounding said medallion, the scrolls *c* surrounding the beaded ornamentation, the converging scroll-like ornamentations *d*, which border the top of the handle and surround and laterally inclose the scrolls *c*, the substantially-parallel threads *e f*, which extend along 25 the lateral edges of the handle from the bowl 30

up to the scroll-like ornamentations above set forth, and the scroll-like pendants *g*, which terminate the lower ends of these threads and extend toward the bowl, these threads *e f* on each side of the handle being so disposed 35 that when viewed in cross-sectional elevation a generally-concave appearance is given to that part of the handle inclosed by said threads, as shown at *h*.

Referring to the reverse side of my newly- 40 designed handle, the leading or material features consist of the converging scroll-like ornamentations *i* at the top of the handle and the substantially-parallel threads *j k* at each side of the handle, said threads being so 45 disposed that when viewed in cross-sectional elevation that portion of the handle inclosed between said threads presents a concave appearance, as shown at *l*.

Having thus described my invention, what 50 I claim as new, and desire to secure by Letters Patent, is—

The design for the handle of a spoon or similar article, as herein shown and described.

In testimony whereof I affix my signature 55 in presence of two witnesses.

FREDERICK PRÉTAT.
